CLAIM

We claim the ornamental design for an information handling system bezel, as shown and described.

DESCRIPTION

FIG. 1 is a front perspective view of the information handling system bezel comprising the present invention; FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a left side perspective view thereof;

FIG. 10 is an upper front perspective view of the information handling system bezel shown in an environment coupled to a housing; and

FIG. 11 is a lower front perspective view of the information handling system bezel shown in an environment coupled to a housing.

FIG. 12 is an enlarged view of portion 12 shown in FIG. 2; and,

FIG. 13 is an enlarged view of portion 13 shown in FIG. 9. Broken lines seen in FIGS. 10-11 that depict an information handling system housing depict environmental subject matter and form no part of the claimed design. Broken lines that encircle portions of FIGS. 2 and 9, and that border the detail views in FIGS. 12-13, indicate outer limits of enlarged areas of the figures and form no part of the claimed design. All other broken lines seen in the drawings depict portions of the information handling system bezel that form no part of the claimed design.
